FOLDING BOX

Edgar L. Stern and Raoul J. Gruenberg,
San Francisco, Calif.

Application September 21, 1931, Serial No. 563,920

2 Claims. (Cl. 229—35)

This invention relates to improvements in folding boxes and more particularly to folding box board products. For further particulars reference is made to the patent to Edgar L. Stern, Number 1,463,448, dated July 31, 1923, entitled 5 Folding box.

The principal object of the present invention is to provide a paper box that may be machine or hand folded and supplied to the trade in a 10 collapsed condition and that may be easily and quickly opened ready for use without any assembling operations by the consumer.

Another object is to construct and arrange the 15 interlocking portions of the box to provide reinforced self-elevating corners that will remain rigid when elevated.

Other objects and advantages will appear as the description progresses.

In this specification and the accompanying 20 drawings the invention is disclosed in its present preferred form. It is to be understood, however, that it is not limited to this form, because it may be embodied in other forms within the purview of the claims following the description.

25 In the two sheets of drawings:

Fig. 1 is a perspective view of a folding box constructed in accordance with this invention and having an integrally hinged lid.

Fig. 2 is a fragmentary enlarged detail of a 30 box corner, interlocked and showing the relative positions of the parts during the act of opening and elevating the corner of a collapsed box.

Fig. 3 is similar to Fig. 2 showing the positions of the parts near the end of the act of opening 35 and elevating a corner of the collapsed box.

Fig. 4 is a similar view showing a side elevation of an elevated corner.

Fig. 5 is a plane view of the box blank.

Fig. 6 is a plane view of a fully collapsed box.

40 Fig. 7 is a cross section of a corner of the box when collapsed, showing the relative positions of the tongue engaging the side slots.

In detail the construction illustrated in the 45 drawings, referring to Fig. 5, comprises a blank of foldable box board longitudinally scored at 1—2, and transversely scored at 3—4—5—6. These score lines divide the blank respectively into the top and bottom 7—8, the ends 9—10 50 and the lock flap 11, in longitudinal alignment, and the sides 12—13 and the locking tongues 16—17—18—19 in transverse alignment respectively on opposite sides of the blank.

The ends of the end flap 11 are rounded at 55 11'—11'' and the corners of the side flaps 12—13

are cut away at 12'—13' to facilitate the closing of the assembled box.

The sides 14—15 are pierced with the obliquely disposed biarcuate or two segmental curve slots 20—21—22—23, starting at a—b and meeting at the apex c, see Fig. 4. The ends of these sides 14—15 are eased off as at 14'—15'. The material removed at that point facilitates the folding and unfolding of the box by removing the frictional contact with the ends 9—10.

10 The tongues 16 to 19 are each cut to a particular pattern, see Fig. 5. Each is severed from the adjacent sides by the cuts 24—25—26—27—28—29, extending from the lateral margins inward to their respective score lines 1—2, whereat they remain hinged to the blank. The outer corners are cut away by the angular notches d—e. These notches are substantially triangular, the bases of the notches d being transverse to the score line 1—2, while the bases of the notches e 20 are oblique to said lines. At the apex of each notch d, the corner is cut away to form the gap f.

15 These tongues 16 to 19 have the neck from e to f, between the angular head g and the base h. The sides i—j of the tongues are parallel with the 25 score lines 4—5—6 and the sides k are parallel with the longitudinal score lines 1—2, for reasons which will be more fully described.

20 The box is assembled by folding the sides 14—15 upward and inward on the lines 1—2, and 30 the ends 9—10 upward and inward on the lines 5—6. This leaves the tongues 16 to 19 projecting laterally. These tongues are bent on the lines 1—2 so that their planes lie parallel with the outer planes of the sides 14—15. The heads 35 g of the tongues are then entered through their respective pierced slots 20 to 23, until their edges i rest upon the bottom 8. The cuts from c to b open to pass the heads g, then close to retain them. This leaves the portions from a to c 40 engaging the necks from e to f. The gaps f engage the cross section of the sides 14—15 at a and cooperate with the closed cut c—b to lock the heads g within the box, by enabling the tabs to lie flat against the sides 14—15. Without 45 these gaps f the corners of the notches d do not "snap" into engagement with the slot at a. When in the flat collapsed condition the necks of the tongues take an offset at 30 (see Fig. 7) equal to the thickness of the paper sides of the box, and 50 will lie flat against these sides when the box is opened, as will be more fully described. The friction of the edges i against the bottom 8 of the box further prevents the lateral displacement of the heads g and the sides 14—15. The 55

bracing of the head at *i* causes the tongue to act as a strut, from A to H, see Figs. 1 and 4, insuring rigidity at the several elevated corners of the open box. The corners of the tongues 5 **16—17—18—19** are cut away as at **16'—17'—18'—19'** to facilitate their entry through the slots at *b*.

When the box corners are interlocked for storage in the flat or collapsed state, as shown in 10 Fig. 6, the procedure is slightly different from that above described. Instead of rotating the heads *g* through the slots **20** to **23**, in the vertical plane, the sides **14—15** are bent over the bottom **8**, see Fig. 2, instead of perpendicular thereto, 15 as in Fig. 1. The operator then enters the heads *g* through the slots by curling the tongues back toward the planes of the ends **9—10** respectively. The continued depression or flattening of the ends **9—10** and sides **14—15** completes the interlocking 20 of the tongues in the slots, which also holds these ends and sides flat against the plane of the bottom **8**, because of the spring tension of the tongues, until released by the act of opening the collapsed box. This interlocking and collapsing 25 of the box is accomplished by a folding machine forming the subject matter of another application for patent about to be filed.

The collapsed box opens automatically into the shape shown in Fig. 1, when the two sides **14—15** 30 are grasped at their centers **X—X**, see Fig. 6, and the sides **14—15** elevated as in Fig. 1. There is enough resiliency in the material of the tongues to cause them to "snap" the several corners up, which opens the box to full capacity.

One great advantage of this invention is that 35 the boxes can be assembled in the flat collapsed condition at the factory and delivered to the trade in convenient bundles. The sales person merely lays a box on the counter, snaps it open, 40 inserts the contents and delivers it to the customer. In this practice neither the sales person nor the customer loses any time in assembling the box.

It is obvious that if desired the trade can receive 45 the blanks, see Fig. 5, and assemble the boxes by hand to utilize the spare time of the sales people and thus save some of the first cost of the boxes.

The form of box illustrated is what is known as 50 a "cake box". The same general form also serves for eggs and many other commodities. The lid **8** hinges at **4**, and when closed the flaps **12—13** pass within the box parallel with the sides **14—15** and the end flap **11** lies within the end **10**. In the collapsed condition the lid **7** may be folded down to

lie above the bottom **8**, or folded back at **4** as shown in Fig. 6.

Suit boxes, flower boxes and similar telescoping boxes in all shapes and sizes can embody this invention. In such cases the lid **7** is omitted at **4**, 5 and two trays of telescoping sizes made as in Fig. 1, of any practical dimensions. When such trays are telescoped together in the usual manner they make a complete, covered box in accordance with this invention. 10

In the present embodiment the tongues have been shown formed on the ends and engaging slots in the sides. The parts may be reversed by forming the tongues on the sides to engage 15 slots in the ends, or the tongues and slots may be alternated at the corners in polygonal or irregular box shapes, without departing from the spirit of the invention.

Having thus described this invention what we claim and desire to secure by Letters Patent is: 20

1. As an article of manufacture, a cardboard box unit in knocked-down collapsed form comprising a bottom, rectangular sides hinged thereto and lying flat upon the bottom, rectangular ends hinged to the bottom and lying upon the 25 end portions of the sides, tongues on the ends projecting through slots in the sides, said sides and ends and tongues when raised to vertical position forming corner constructions, the ends of the tongues being of such length as to remain 30 in engagement with the bottom when the tongues are in vertical position, said tongues where passed through the sides having such form as to constitute a positive hook like engaging means resisting separation of the ends from the sides. 35

2. As an article of manufacture, a cardboard box unit in knocked-down collapsed form comprising a bottom, sides and ends hinged to the bottom, the sides lying flat upon the bottom, said ends lying flat upon the end portions of the sides, 40 said sides having slots therein, tongues on the ends projecting through said slots, said sides, ends and tongues when raised to vertical position forming corner constructions, the ends of the tongues being of such length as to remain in engagement with the bottom when the tongues are 45 in vertical position, said tongues having hook like elements which extend above the upper ends of said slots within the box when in vertical position, and hold the lower ends of the tongues 50 against the bottom.
